[57] **CLAIM**

The ornamental design for an anode for cathodic protection of chain links, as shown and described.

DESCRIPTION

FIG. 1 is a top plan view of an anode for cathodic protection of chain links showing my new design;
FIG. 2 is a side elevational view thereof;
FIG. 3 is an end elevational view thereof;
FIG. 4 is a bottom plan view thereof;
FIG. 5 is a sectional view taken in the direction of the arrows along line 5—5 in FIG. 1.
